US00D922797S

(12) **United States Design Patent** (10) **Patent No.:** **US D922,797 S**
Liu (45) **Date of Patent:** **** Jun. 22, 2021**

(54) **SEAT CUSHION**

(71) Applicant: **ZHONGSHAN HUITING TECHNOLOGY CO., LTD.**,
 Zhongshan (CN)

(72) Inventor: **Wenjia Liu**, Zhongshan (CN)

(73) Assignee: **ZHONGSHAN HUITING TECHNOLOGY CO., LTD.**,
 Zhongshan (CN)

(**) Term: **15 Years**

(21) Appl. No.: **29/757,800**

(22) Filed: **Nov. 10, 2020**

(51) LOC (13) Cl. **06-09**

(52) U.S. Cl. .... **USPC D6/601**

Primary Examiner — Sanjeev Paul

(57) **CLAIM**

The ornamental design for a seat cushion, as shown and described.

DESCRIPTION

FIG. 1 is a perspective view of a seat cushion showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.
